COMBINED CAMPER, BOAT AND TRAILER

William P. Gardiner, Council Bluffs, Iowa, assignor to General American Corporation, Council Bluffs, Iowa

Filed Feb. 22, 1973, Ser. No. 334,719

Term of patent 14 years

Int. Cl. D12—10, 06

U.S. Cl. D12—3

FIG. 1 is a front perspective view of a combined camper, boat and trailer showing my new design; and

FIG. 2 is a rear perspective view thereof.

I claim:

The ornamental design for a combined camper, boat and trailer, as shown.
